UNITED STATES PATENT OFFICE

2,061,059

FOUNTAIN PEN

Adolph E. Carlson, Burbank, Calif.

Application September 21, 1935, Serial No. 41,571

7 Claims. (Cl. 120—42)

This invention relates to improvements in fountain pens.

The general object of the invention is to provide a fountain pen having a novel ink container.

5 Another object of the invention is to provide a novel ink container for a fountain pen.

Other objects and the advantages of this invention will be apparent from the following description wherein:

10 Fig. 1 is a side elevation of my improved fountain pen partly in section;

Fig. 2 is an enlarged fragmentary central section through the pen showing the ink vial being positioned in the barrel;

15 Fig. 3 is a view similar to Fig. 2 showing the ink vial fully positioned in the barrel; and

Fig. 4 is a view similar to Fig. 3 showing a modification of my invention.

Referring to the drawing by reference characters I have indicated my improved fountain

20 pen generally at 10. As shown the fountain pen

10 includes a barrel portion 12 having a recess

13 therein which opens through one end of the

25 barrel and a reduced communicating recess 14

which opens through the opposite end of the

barrel. At the juncture of the recesses 13 and

20 the barrel includes a shoulder 15 which is

shown as bevelled. Adjacent its outer end the

recess 13 includes a threaded section 16 and ad-

30 jacent the opposite end of the barrel the barrel

includes an externally threaded portion 17.

Adjacent the threads 17 a pen point 18 which

35 may be of any desired type is secured to the

barrel 12 by a plug member 19. This plug 19

includes a body portion 20 which is positioned in

the recess 14 and includes a reduced lip portion

recess 26. A cap 28 of the usual type is shown as removably secured to the barrel 12 by engagement with the threads 17. At 29 I have indicated an ink vial which includes a hollow cylindrical body portion 30 open at one end and 5 closed at the opposite end. Adjacent the closed end the vial includes an enlarged threaded portion 31 and an enlarged head portion 32. Adjacent the open end of the vial the body 30 has an external circular groove 33 therein. 10

For closing the open end of the vial I provide a cap member 34. The cap 34 is cup-shaped and is made of rubber and fits over the open end of the body 30. The cap 34 includes an enlarged annular flange portion 35, a portion of which is 15 positioned in the groove 33 and tightly engages the body 30. The bottom of the cap 34 includes a thickened portion 36 which extends into the body 30. The vial 29 is adapted to be filled with suitable fountain pen ink. 20

In operation a vial 29 is inserted in the barrel recess 13 with the vial cap 34 directed towards the spur 22. When the vial cap 34 engages the pointed end of the spur 22 and the vial is moved further into the barrel the pointed end of the 25 spur 22 punctures the bottom of the cap and passes through the thickened portion 36 into the interior of the vial. As the vial is moved into the barrel the vial threads 31 engage the barrel threads 16 and then the vial is rotated to move 30 the cap flange 35 into tight engagement with the shoulder 15 of the barrel.

When the vial is fully positioned in the barrel the apertures 27 in the spur 22 are positioned in the vial beyond the cap so that the ink in the 35 vial will, when the pen is used to write, flow through the apertures 27 into the recess 26 and then into the ink groove 24. When the ink in the vial is exhausted the vial is removed from the barrel and another vial inserted thereinto. 40 When the vial is removed the elasticity of the cap closes the puncture made by the spur 22. Thus should any ink remain in the vial it will not leak out when the vial is removed from the pen barrel. 45

In Fig. 4 I have indicated a modified form of my invention generally at 37. As shown the barrel, plug and pen point of the device 37 are similar to those of the device 10 and like portions thereof are indicated by similarly primed reference numerals. In the device 37 I provide a cap member 38 for closing the open end of the barrel 12'. The cap 38 includes an externally threaded portion 39 for engagement with the barrel threads 16' and an enlarged portion 40. The 50 55

cap 38 has a recess 41 therein which opens through the end thereof opposite the head portion 40. Positioned in the recess 41 I provide a pad 42 which may be made of sponge rubber and a disk 43 which is made of a suitable hard material. The pad 42 is preferably cemented to the cap at the bottom of the recess 41 and the disk 43 is preferably cemented to the pad 42.

For use in the device 37 I provide an ink vial 45 which is shown as a hollow tube 46 which may be made of metal and is closed at one end by a hemispherical end wall 47. Adjacent its open end the tube 46 includes an enlarged peripheral flange 48. The open end of the tube 46 is closed by a cap 49 which is cup-shaped and made of rubber. The cap 49 includes an enlarged flange portion 50 which engages the tube flange 48. The bottom of the cap includes a thickened portion 51 which extends into the tube.

20 In operation the cap 38 is removed from the barrel and a vial 45 is positioned in the barrel recess 13 with the vial cap 49 engaging the end of the spur 22'. The barrel cap 38 is then positioned in the end of the barrel with the curved end 47 of the vial positioned in the cap recess 41 and engaging the disk 43. Thereafter the cap 38 is rotated to engage the cap and barrel threads. Thereafter as the cap is further rotated it moves the vial further into the barrel and causes the pointed end of the spur 22' to puncture the vial cap 49 and enter the tube 46. At the same time the vial cap is being punctured the pad 42 is being compressed so that when the cap 38 is in a fully closed position the pad 42 through 30 the disk 43 resiliently urges the vial towards the shoulder 15' thereby compressing the flange 50 of the vial cap between the shoulder 15' and the tube flange 48.

From the foregoing description it will be apparent that I have provided a novel fountain pen and vial which is simple in construction and highly efficient in use.

Having thus described my invention I claim:

1. In a fountain pen, a barrel portion having a 45 recess therein opening through one end thereof and a second recess opening through the opposite end of said barrel and communicating with said first recess and having a seat shoulder at the juncture of said recesses, said first recess including a threaded portion adjacent the outer end thereof, a plug member in said second recess, a pen point mounted on said plug, said plug including a spur portion having a pointed end positioned in said first recess beyond said shoulder, said plug having a passageway therein extending from adjacent said pointed end to the nibs of said pen, said spur portion having a plurality of apertures therein adjacent the pointed end thereof and communicating with said plug 50 passageway, a vial, said vial including a hollow body portion closed at one end and open at the opposite end, said vial body adjacent said closed end including an enlarged threaded portion and an enlarged head portion, said vial body adjacent said open end having a peripheral groove therearound, a cap member closing said open end of said vial and made of resilient material with an enlarged annular flange at the end thereof, said cap being positioned over the open 55 end of said vial body with said cap flange positioned in said body groove, said vial being positioned in said barrel recesses with said vial threads engaging said barrel threads and with said cap flange tightly engaging said barrel shoulder and with said spur member extending 70 75

through said vial cap with said spur apertures positioned in said vial body beyond said cap bottom so that said apertures form communicating passageways between said plug passageway and the interior of said vial body.

2. For use in a fountain pen, a vial member including a hollow body portion closed at one end and open at the opposite end, said vial body adjacent said open end including an enlarged peripheral flange portion, a cap member for closing said open end of said vial body, said vial cap being made of a resilient material and being cup-shaped with an enlarged flange at its upper end, said vial cap being positioned over the open end of said vial body with said flange thereof engaging said flange of said vial body.

3. A fountain pen barrel having a recess therein opening through one end thereof and a second recess opening through the opposite end of said barrel and communicating with said first recess and having a seat shoulder at the juncture of said recesses, said first recess including a threaded portion adjacent the outer end thereof, a plug member positioned in said second recess adjacent the outer end thereof, a pen point mounted on said plug, said plug including a conical spur portion having the pointed end thereof positioned in said first recess beyond said shoulder, said plug having a passageway therein extending from adjacent said pointed end to below the slit of said pen, said spur portion having a plurality of apertures therein adjacent the pointed end thereof and communicating with said plug passageway, a cap member for closing the open end of said barrel, said cap having a recess therein and including an externally threaded portion and an enlarged head portion, a disk member in said cap recess between the bottom thereof and said disk, said cap being positioned in said first barrel recess with said cap threads engaging said barrel threads.

4. In a fountain pen, a hollow barrel having a shoulder therein, said barrel including a threaded portion adjacent one end thereof, a plug member positioned in said barrel adjacent the other end thereof, a pen point engaging said plug, said plug including a conical spur portion with a pointed end positioned beyond said shoulder, said plug having a passageway therein extending from adjacent said pointed end to below the nibs of said pen, a threaded cap member closing the threaded end of said barrel, and having a recess therein, a disk member in said cap recess, a resilient member in said cap recess between the bottom thereof and said disk, a vial including a hollow body portion closed at one end and open at the opposite end, said vial body adjacent said open end including a peripheral flange portion, a resilient cap member closing the open end of said vial and having an enlarged flange at its upper end engaging said flange of said vial body, said vial being positioned in said barrel with the closed end of said vial positioned in said cap recess and with said vial cap flange engaging said barrel shoulder and with said spur member extending through the bottom wall of said vial cap with said spur positioned in said vial body beyond the vial cap.

5. In a fountain pen, a barrel portion having a recess therein opening through one end thereof and a second recess opening through the opposite end of said barrel and communicating with said first recess and having a seat shoulder at the juncture of said recesses, a pen point mounted

on said barrel portion, a vial, said vial including a hollow body portion open at one end, said vial body being cylindrical adjacent said open end, a cap member closing said open end of said vial, said cap being made of resilient material, said cap including a central body portion and a cylindrical skirt engaging the outer wall of the vial, said skirt having an enlarged flange at the free end thereof, said skirt flange having its outer portion tightly engaging said barrel seat shoulder, said barrel including a spur member extending through said vial cap body portion.

6. In a fountain pen, a barrel portion having a recess therein opening through one end thereof and a second recess opening through the opposite end and communicating with said first recess, said barrel portion including a seat shoulder at the juncture of said recesses, a pen point mounted on said barrel portion, a vial, said vial including a hollow body portion open at one end, said vial body being cylindrical adjacent said open end having a peripheral groove therearound, a cap closing said open end of said vial, said cap being made of resilient material, said cap including a central body portion thicker at the middle than at the sides and including a cylindrical skirt engaging the outer wall of the vial, said skirt having an enlarged flange at the free end thereof, said skirt flange having its inner portion positioned in said body groove, said cap flange having its outer portion tightly engaging

said barrel seat shoulder, said barrel including a spur member extending through said vial cap body portion.

7. In a fountain pen, a barrel portion having a recess therein opening through one end thereof and a second recess opening through the opposite end of said barrel and communicating with said first recess and having a seat shoulder at the juncture of said recesses, a plug member in said second recess, a pen point on said plug, said plug including a spur portion having a pointed end positioned in said first recess beyond said shoulder, said plug having a passageway therein, said spur portion having an aperture therein communicating with said plug passageway, a vial, said vial including a hollow body portion closed at one end and open at the opposite end, said vial body adjacent said closed end including a head portion, said vial body being cylindrical adjacent said open end, a cap member closing said open end of said vial and made of resilient material with an enlarged annular flange at the end thereof, said cap being positioned over the open end of said vial body with said cap flange engaging said seat shoulder, and with said spur member extending through said vial cap with said spur aperture positioned in said vial body beyond said cap so that said aperture forms a communicating passageway between said plug passageway and the interior of said vial body. 30
